UNITED STATES PATENT OFFICE.

SPENCER M. BUMP, OF LAKEWOOD, OHIO, ASSIGNOR TO THE BETTCHER STAMPING & MANUFACTURING COMPANY, OF CLEVELAND, OHIO, A CORPORATION OF OHIO.

CHAIR-SEAT MOUNTING.

Application filed October 15, 1928. Serial No. 141,732.

This invention relates to pedestal chairs of the swiveling type, and particularly to chairs of the type which may be inclined or rocked backwardly against the tension of a spring tending normally to hold the chair back and seat in an upright position. The invention relates more particularly to the rocking connection between the bolts, on which the said spring or springs act to resist the rearward rocking movements of such chair seats, and the abutments or cross plates through which said bolts extend and which are usually supported indirectly by the post or pedestal.

It is the general purpose and object of the invention to provide, in such installations, a rocking connecting member which is simple in construction, which can be produced economically and by a stamping operation; and which is stronger than the built-up connecting members which are in general use.

I accomplish the foregoing objects in and through the connecting member set forth in detail hereinafter, reference being had to the drawings, wherein Fig. 1 represents a sectional elevation of parts of a chair-seat frame, showing the manner in which the said frame is supported from the post or pedestal and the manner in which the aforesaid connecting member is used; Fig. 2 is a plan, with parts broken away, of the frame and parts shown in Fig. 1, showing my connecting member and the parts cooperating therewith; and Fig. 3 is a side elevation, Fig. 4 an end elevation, and Fig. 5 a bottom plan view of the aforesaid connecting member.

Describing by reference characters the various parts shown in the drawings, 1 denotes the post or pedestal of a chair of the ordinary swivel type, the upper end of the said post or pedestal being shown as reduced in diameter at 2 to form a neck, with a shoulder 3 beneath said neck on which is mounted the bottom plate 4 of a yoke, the said yoke being U-shaped and having the upwardly extending side flanges 5.

6 denotes a pair of angular seat brackets which are adapted to support the chair seat in the ordinary manner, the upper flanges 6^a of the said brackets being provided with apertures 6^b for the reception of bolts or other means for securing the chair seat thereto. Secured to the vertical flanges of the seat brackets, as by rivets 7, are the side

flanges 8 of a cradle or channel-shaped connecting member, the rear web of which is shown at 9. The lower forward ends of the sides 8 are supported from the sides 5 of the yoke by means of a cross pin 10. A cross bolt 11 which is connected to the vertical flanges of the brackets 6 extends through slots 5^a in the opposite sides of the yoke 4, 5, thereby serving to limit the rocking movement of the chair seat upon the cross pin 10.

At its upper end, the neck 2 is reduced in diameter, as shown at 2^a, thereby providing a shoulder 2^b beneath such reduced end, 12 denotes a cross plate having a substantially horizontal lower end which has an aperture 12^a therein adapted to fit over the reduced end 2^a of the post or pedestal 1, which reduced end may be headed to form an integral rivet, shown at 2^c. The cross plate 12 extends upwardly and forwardly from the bottom portion thereof and is provided with a vertical extension having a recess 12^b through which the bolt 13 extends. This bolt has secured to its rear end a cross plate 14 which receives therewithin the rear ends 80 of the springs 15, the front ends of the springs bearing against the rear web 9 of the cradle and being retained in position by lugs 9^a projecting rearwardly from the said web 9.

The front end of the bolt 13 projects through the connecting member, referred to hereinbefore, being provided with a thread on such front end on which is threaded the hub 16^a of a hand wheel 16, the hub bearing against the central portion of the said connecting member, which will now be described.

The connecting member is preferably made from sheet metal by a stamping operation by which it is provided with a forwardly-projecting arched or dome-shaped central body 17 having an aperture 18 therethrough, the sides of the dome being extended and pressed together to form 100 double-walled arms 19, the rear end of each arm being provided with a double-wall bearing edge 20 which edges are adapted to engage and rock upon the vertical part 12^b of the cross plate 12.

The general construction and arrangement of parts, with the exception of the particular construction of the rocking connection 17-20 is old in the art; but a connecting member constructed and shaped as shown 110

and described herein is of decided advantage in that said member may be made cheaply, by a few stamping operations, the central portion of said member surrounding the 5 aperture 18 constituting an arch-support thrust bearing which is very strong and capable of sustaining all thrusts and strains exerted thereagainst by the sleeve 16^a, while the shape and construction of the arms 19 is 10 such as to secure ample strength in these parts to withstand such thrusts and strains.

Having thus described my invention, what I claim is:

1. A rocking connecting member for use 15 with one or more springs arranged to resist the backward movement of swivel chairs and with a bolt having a cross plate engaging such spring or springs and extending forwardly and beyond a cross member carried 20 by the seat assembly, the said connecting member being formed from a single piece of metal having a forwardly projecting dome-shaped central portion provided with an aperture therethrough, the portion of 25 such dome surrounding the said aperture, constituting an arch-supported thrust surface for engagement by an adjustable member on the front of said bolt, said connecting member having integral extensions adapted 30 to bear against said cross member.
2. A rocking connecting member for use 35 with one or more springs arranged to resist the backward movement of swivel chairs and with a bolt having a cross plate engaging such spring or springs and extending forwardly and beyond a cross member carried 40 by the seat assembly, the said connecting

member being formed from a single piece of metal pressed to a shape to provide a central 45 forwardly-projecting dome-shaped portion having an aperture therethrough for the reception of the said rod, the portion of such dome surrounding the aperture constituting an arch supported thrust surface for engagement by an adjustable member on the front 50 of said bolt, the said connecting member comprising also double-walled lateral extensions 55 constituting arms provided at their ends with bearings adapted to engage said cross member.

3. A rocking connecting member for use 60 with one or more springs arranged to resist the backward movement of swivel chairs and with a bolt having a cross plate engaging such spring or springs and extending forwardly and beyond a cross member carried 65 by the seat assembly, the said connecting member being formed from a single piece of metal having a central dome-shaped portion provided with side flanges, the dome-shaped portion having an opening therethrough for the passage of said rod and provided with an arch-supported thrust surface 70 surrounding said aperture and adapted to take the thrust of the rod through the engagement therewith of a member adjustably mounted on the front thereof, the side flanges being extended from such dome on both sides thereof and pressed together to form legs, each leg terminating in a bearing 75 adapted to engage said cross member.

In testimony whereof, I hereunto affix my signature.

SPENCER M. BUMP.
